E. PANZA

DEVICE FOR OPENING SEALED PACKAGES

Filed Nov. 28, 1923

Eugene Panza.

Harry M. Brown.

ATTORNEY.

Patented Nov. 18, 1924.

UNITED STATES PATENT OFFICE.

EUGENE PANZA, OF SPRINGFIELD, MASSACHUSETTS.

DEVICE FOR OPENING SEALED PACKAGES.

Application filed November 28, 1923. Serial No. 677,382.

To all whom it may concern:

Be it known that I, EUGENE PANZA, at present a subject of the King of Italy, but having declared my intentions of becoming a citizen of the United States, residing at Springfield, in the county of Hampden and State of Massachusetts, have invented new and useful Improvements in Devices for Opening Sealed Packages, of which the following is a specification.

This invention relates to improvements in receptacle, and particularly in receptacles for containing cigarettes.

An object of the invention is to provide and so construct the receptacle in order that it may be readily opened to permit a cigarette to be removed, and, without destroying the contents of the package, or, leaving the receptacle in an unsightly appearance.

Heretofore, it has been, and is now, a common expedient for the user to open a package of cigarettes by tearing or breaking off the upper edge of the package with his fingers. This operation not only destroys the appearance of the package after it is opened, but, oftentimes the ends of the cigarettes are broken which permits a portion of the filler or contents of the cigarette to fall out.

My present invention is designed to overcome these obvious objections and to so construct the package or wrapper of the package so that it may be readily opened and without breaking the contents.

In general, my invention consists in securing to the wrapper portion of the package a thin strip of ribbon, whereby when one end of the ribbon is pulled the wrapper may be severed, as it were, or torn along a line, or plane, that corresponds with one that is parallel to the closed or upper end of the package and a short distance below the ends of the cigarettes. Any suitable means may be employed for securing the strip of ribbon to the paper and tinfoil parts which make up the wrapper, as by means of a toothed wheel or implement, as will be fully described in the specification and specifically set forth in the claims.

Referring briefly to the drawings:

Fig. 1 is a perspective of a package of cigarettes showing the invention applied thereto, and with the package sealed in the usual manner.

Fig. 2 is a perspective showing the pack-

age partially opened with the upper ends of the contents exposed.

Fig. 3 is a developed plan view of the two parts of the wrapper with the strip of ribbon placed on the paper and before securing it to the two parts, and

Fig. 4 is a perspective view showing the ribbon secured to the two parts of the wrapper.

Referring to the drawings in detail:

1 designates the inner layer or sheet of specially prepared paper which is placed against the cigarettes in the package, 2 a layer of tin foil which is placed against the inner lever of paper, and 3 is the usual outer lithographical wrapper which bears the name of the manufacturer; the meeting or overlapping edges of this outer wrapper is indicated at 4. The cigarettes within the packages are indicated at 5, and 6 designates a narrow strip of ribbon that is secured to the layers 1 and 2 of paper and tinfoil. Fig. 3 indicates these layers as developed or spread out in a horizontal plane. The strip of thin narrow ribbon 6 is secured to the layers 1 and 2 by passing a suitable tool over and lengthwise of the ribbon, and, at the same time applying sufficient pressure for the purpose of forcing the threads or strands of the ribbon into the inner layer of paper 1 and also into the tinfoil 2 as indicated in Fig. 4. The creases or indentations produced by forcing or substantially imbedding the strands of the ribbon into the layers of paper and tinfoil are indicated in Fig. 4 at 8. This operation serves to attach the strip of ribbon to the layer of paper and tinfoil with the result that when the free end 6' of the ribbon is pulled, as shown in Fig. 1 the upper end portion of the layer of paper 1 and tinfoil 2 will be severed or torn off leaving the upper ends of the cigarettes 5 exposed, as shown, whereby the user may readily remove them without in any way injuring the wrapper of the cigarettes or spilling their tobacco contents. It is to be understood that the line or plane of separation is substantially at the upper edge of the outer wrapper 3. The upper edges of the inner paper wrapper 1 and tinfoil 2 are folded onto the upper ends of the cigarettes in the usual manner as indicated by the dotted lines 9 in Fig. 1. The usual internal revenue stamp is indicated at 10. This is severed when the free end of the strip of ribbon 6 is pulled.

Fig. 2 is a perspective view showing the package partially opened with the upper ends of the contents exposed. The upper edges of the inner paper wrapper 1 and tinfoil 2 are folded onto the upper ends of the cigarettes in the usual manner as indicated by the dotted lines 9 in Fig. 1. The usual internal revenue stamp is indicated at 10. This is severed when the free end of the strip of ribbon 6 is pulled.

ribbon is pulled as shown. If desired, only a portion of the upper end of the wrappers 1 and 2 may be torn as indicated in Fig. 2 at 11 which may be folded back again, after 5 a cigarette has been removed as readily understood. The free end 6' of the strip of ribbon is preferably located adjacent the edge of the revenue stamp and the adjacent edges 4 of the outer wrapper 3 for affording 10 convenience in assembling and for mutilating the stamp when strip is pulled as shown in Fig. 2.

The end of the strip of ribbon 6 is provided with a tag 12 which presents a finished 15 appearance, and, if desired, may be used for advertising purposes. By reason of the fact that the threads or strands of the ribbon are intimately associated or connected with the paper and tinfoil it will therefore 20 be seen that when the strip of ribbon is pulled the inner layer of paper and the layer of tinfoil will be completely severed or torn off so as to leave a smooth upper edge.

It will therefore be seen from this description 25 that I have provided a very convenient and inexpensive construction for opening a package of cigarettes or the like and without in any way destroying the appearance of the package or its contents. It 30 is to be understood that my improvement of opening a sealed package is not limited to packages containing cigarettes but may, of course, be employed for opening packages containing other commodities or articles.

What I claim is:

1. A sealed package provided with layers of wrapping material, means for removing the layers comprising a strip of material having strands, the strands being 40 embedded into the said layers, whereby when the strip is pulled the layers will be torn or severed by the strip.

2. A sealed package having a plurality of layers of wrapping material, a strip of fibrous material intimately and permanent- 45

ly connected to the said material by applying pressure to the strip and the layers whereby when the strip is pulled the layers will be severed or torn along the line of the strip. 50

3. A sealed package comprising a plurality of layers of wrapping material, means to permit the layers along a line, or plane parallel with one end of the package to be separated comprising a strip of fibrous material which is embedded into the layers whereby when the strip is pulled the layers will be torn or separate along the line of the strip, as described. 55

4. A device for removing one end of a package having a plurality of layers of wrapping material, comprising a strip of material that is embedded into all of the layers by pressure, whereby when the strip is pulled the layers will be separated along the line of the strip. 60

5. A device for removing the wrapping material of a package having a layer of paper and a layer of tinfoil thereon, which consists in permanently attaching a strip of flat fibrous material as a ribbon, to the layer of paper and tinfoil by applying pressure to the said strip whereby the fibres of the strip are embedded or forced into the layers. 70

6. A device for removing a layer of paper and a layer of tinfoil from a package which consists in permanently attaching a strip of fibrous material to the layers by placing the strip on the layers and applying pressure to the strip, whereby when the strip is pulled the said layers are separated or torn along the line of the attached strip. 75

7. As an article of manufacture a wrapper for a package comprising a layer of paper, a layer of tinfoil and a strip of fibrous material embedded into the two layers for the purpose of removing a portion of the layers when the strip is pulled. 80

EUGENE PANZA.
